(57) **CLAIM**

The ornamental design for a multi cleaning kit for electronic products, as shown and described.

DESCRIPTION

FIG. 1 is a perspective view of a multi cleaning kit for electronic products showing my design;

FIG. 2 is an exploded view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged detail view of the portion designated area 9 in FIG. 2.

The dashed broken lines shown in the drawings depict portions of the multi cleaning kit for electronic products and form no part of the claimed design. The dot-dashed broken lines in the drawings indicates cutoff boundaries for the enlarged detailed portion views and form no part of the claimed design.

1 Claim, 9 Drawing Sheets
